DESIGN FOR A SLED

Zachariah Adam Hall, Guelph, Ontario, Canada

Application November 10, 1933, Serial No. 49,692
In Canada September 6, 1933

Term of patent 3½ years

To whom it may concern:

Be it known that I, Zachariah Adam Hall, a British subject, residing at the city of Guelph, in the county of Wellington and Province of Ontario, Dominion of Canada, have invented a new, original, and ornamental Design for a Sled, of which the following is a specification, reference being had to the accompanying drawing, forming a part thereof, in which:—

Fig. 1 is a top perspective view of a sled, showing my new design; and

Fig. 2 is a bottom perspective view thereof.

I claim:

The ornamental design for a sled substantially as shown.

ZACHARIAH ADAM HALL.
